UNITED STATES PATENT OFFICE.

HARRY R. ATWATER, OF CLEVELAND, OHIO, ASSIGNOR TO THE OSBORN MANUFACTURING COMPANY, OF CLEVELAND, OHIO, A CORPORATION OF OHIO.

ROTARY BRUSH.

SPECIFICATION forming part of Letters Patent No. 727,256, dated May 5, 1903.

Application filed May 14, 1902. Serial No. 107,239. (No model.)

To all whom it may concern:

Be it known that I, HARRY R. ATWATER, a citizen of the United States, and a resident of Cleveland, county of Cuyahoga, and State of Ohio, have invented a new and useful Improvement in Rotary Brushes, of which the following is a specification, the principle of the invention being herein explained and the best mode in which I have contemplated applying that principle, so as to distinguish it from other inventions.

My invention relates to brushes such as used for buffing or other purposes; and its object is to produce a brush of very simple construction the bristles or other abrading elements whereof are formed in sections and assembled to form a complete brush upon a hub, in which hub these sections are attached in an improved manner.

The annexed drawings and the following description set forth in detail certain means embodying the invention, such disclosed means constituting but one of various mechanical forms in which the principle of the invention may be used.

In said annexed drawings, Figure 1 represents a longitudinal cross-section of a brush constructed in accordance with my invention. Fig. 2 represents an end elevation of the same, portions being broken away, as indicated, to disclose more fully its construction.

Referring to the parts by letters, A represents the body or hub of the brush, which is preferably made of cast-iron or similar material and substantially cylindrical in form. It is provided, as indicated, with a central boss or sleeve a^1 , to which it is integrally connected by suitable webs a^1 . This boss a^1 is provided with a suitable bore a^2 , which adapts the brush to be mounted upon a mandrel or spindle. The hub A, preferably at its ends, is provided with radial flanges a^3 , which project inwardly, as indicated, at a^4 , whereby they form annular channels or recesses B, extending continuously around the hub. At one point, however, there is provided a removable section C, which extends longitudinally of the hub and which is received by a

groove or recess a^5 in the cylindrical wall a^5 . At its extremities this member is provided with flanges c , which are formed substantially similarly to the flanges of the hub A, so that recesses c^1 are formed, which register with and conform to the aforesaid recesses B B of the hub, as will be readily understood. This member is further provided with ears $c^2 c^2$, which project toward the center of the hub and receive screws D, which are secured in the webs of the hub for retaining the section in place.

The outer or bristle portion of the brush is formed of removable sections E, the bristles e whereof are preferably of wire and fastened to a base F, which is formed, preferably, of stout twisted wires f' . As indicated, the bristles are caught between the strands f' of the wire. The extremities $f f$ of the backs project beyond the bristles e and are adapted to be received by the annular recesses B. The section C having been first removed, these sections E are introduced into the recesses just above the groove a^5 , passed around the brush one after the other, and placed parallel with the hub-axis, this operation being continued until a complete and compact brush is formed or built up, as it were, in this manner. After the last section necessary to complete the brush has been attached in this way a brush-section is placed in the section C and the latter replaced and secured by means of the screws D, as stated. In this manner a very simple but durable brush is produced, and such a construction as this is most advantageous where certain of the abrading devices or sections wear out before others, for they may be readily replaced by new ones, or the entire sets may be replaced.

Other modes of applying the principle of my invention may be employed instead of the one explained, change being made as regards the mechanism herein disclosed, provided the means stated by the claim or the equivalent of such stated means be employed.

I therefore particularly point out and distinctly claim as my invention—

A brush comprising in combination, a hub

having a substantially cylindrical outer face, said face having a longitudinal recess, outwardly-projecting flanges carried by said hub and forming annular recesses, a removable section lying within said longitudinal recess, and having projecting portions registering with said flanges, and members constituting backs of brush-sections, said members being

disposed longitudinally around said cylindrical face, the extremities of said members lying within said annular recesses.

Signed by me this 10th day of May, 1902.
HARRY R. ATWATER.

Attest:

D. T. DAVIES,
A. E. MERKEL.
